UNITED STATES PATENT OFFICE.

LOUIS F. JACKSON, OF DENVER, COLORADO, ASSIGNEE, BY MESME ASSIGNMENTS, TO THE COLORADO BUILDERS SUPPLY COMPANY, OF DENVER, COLORADO, A CORPORATION OF COLORADO.

BUILDING-PARTITION.

1,057,431.

Specification of Letters Patent.

Patented Apr. 1, 1913.

Application filed September 5, 1911. Serial No. 647,728.

To all whom it may concern:

Be it known that I, LOUIS F. JACKSON, a citizen of the United States, residing in the city and county of Denver and State of Colorado, have invented certain new and useful Improvements in Building-Partitions; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to building partitions, where a relatively thin fire-proof board is applied to vertically-disposed studs in order to form a support for the plaster of walls. This board is called "plaster board", 20 and, in order to make the partitions fire-proof, it is used instead of the ordinary lath applied to studs to support the plaster.

25 My present invention is employed in connection with partitions of the aforesaid character and heretofore illustrated and described in connection with Letters Patent of the United States No. 998,293, issued to me July 18, 1911; and an application filed by me July 29th, 1911, Serial No. 641,321.

30 The features of my present improvement, as set forth in this specification, will be illustrated and described in connection with the specific construction disclosed in the aforesaid application, though it may be advantageously employed in connection with any suitable means for securing the plaster board, or similar sheeting, to partition studs.

35 The novel feature of my present improvement consists of a sort of U-shaped clip, 40 adapted to straddle the stud, on one side, and hook over the plaster board applied to the stud on the opposite side. These clips are employed in connection with the studs 45 located intermediate the plaster board joints, and, consequently, intermediate the opposite vertical edges of the plaster board sections. The vertical meeting edges of these sections are connected by the use of the 50 fastening devices illustrated in my aforesaid application, but, as disclosed in said application, no provision was made for connecting the plaster boards with the portions of the studs located intermediate the opposite 55 vertical edges of the plaster board sections.

My present invention makes provision for such connection by the employment of a very simple and inexpensive clip, which will hereinafter be fully described in detail, reference being made to the accompanying 60 drawing, in which is illustrated an embodiment thereof.

In this drawing: Figure 1 is a perspective view of one form of my improved clip. Fig. 2 is a cross section, taken through a stud 65 with plaster board shown in connection therewith, the clip being applied to the stud and board. Fig. 3 is a side elevation of the same, or a view looking in the direction of arrow 3, Fig. 4. Fig. 4 is a section, taken 70 on the line 4—4, Fig. 2. Fig. 5 is a view, looking in the direction of arrow 5, Fig. 4. Fig. 6 is a perspective view in detail, illustrating a modified form of clip. Fig. 7 is a detail view, illustrating still another form 75 of retaining clip. Fig. 8 is a similar view, illustrating a clip of the same shape as in Fig. 7, but formed of a flat piece of material, instead of a round wire. Fig. 9 is a fragmentary side elevation of a partition, 80 showing the form of clip illustrated in Fig. 7 applied. This is a view looking in the direction of arrow 9, Fig. 10. Fig. 10 is a section, taken on the line 10—10, Fig. 9, looking toward the left, or in the direction 85 of the arrow. Fig. 11 is a view looking in the direction of arrow 11, Fig. 10. Fig. 12 is an elevation, shown on a relatively small scale, illustrating the use of my improved 90 clips, shown in connection with a plaster board partition, where the sections of board are arranged to break joints. Fig. 13 is a similar view, where the plaster boards are differently arranged, or where the vertical joints between the board sections are arranged in vertical lines, rather than in staggered relation, as illustrated in Fig. 12. Fig. 14 is a section, taken on the line 14—14, Fig. 12.

95 The same reference characters indicate 100 the same parts in all the views.

Let the numeral 5 designate a stud, which it may be assumed is vertically disposed between the joists of the floor and ceiling of a room. As shown in the drawing, this stud 105 is composed of channel iron, though it may be of any suitable or desirable form. The plaster board 6 is applied to one of the vertical faces of a stud. My improved clip 7 is formed of a piece of wire, which may be 110

either round, flat, or of any other desirable shape in cross section.

In Fig. 1, the clip is made of wire, round in cross section, while in Fig. 6, it is shown flat. This clip is first bent to form a U-shaped device having two parallel arms 8 connected by a bend 9. It is afterward bent intermediate the extremities of the arms 8, as shown at 10, whereby it is V-shaped. In applying the clip to the stud, the arms 8 are caused to straddle the stud, while their outer portions 12 engage the plaster board on the opposite side from the stud. By virtue of the peculiar shape of these clips, they are caused to clamp the board to the stud as the clips are forced downwardly on the stud, since the farther the clip is moved downwardly, the tighter it clasps or clamps the two connected parts by virtue of the V-shaped construction of the clip, as heretofore described. As the form of construction illustrated in Figs. 1 and 6 is used in exactly the same manner, a separate description of the use and application of these two forms of clip is not considered necessary. It may be stated, however, that the forms of clip illustrated in Figs. 1 to 6, inclusive, are especially advantageous in connection with a partition where the plaster board sections are arranged as illustrated in Fig. 12, in which the plaster board sections are staggered, so to speak. For instance, the two sections,—see Fig. 12,—and designated 6, have their vertical edges connected with a stud 5 by means of clips 13 and keys 14, as illustrated in my aforesaid application. Now, directly above the meeting edges of the two sections 6 is a third section 6, which is so arranged that the center of the section is in line with the two meeting edges of the section 6 below. In this event, my improved clip 7 is applied to the stud 5 at both the upper and lower edges of the upper section 6, the hooked extremity extending downwardly in engagement with the plaster board, where the clip is applied to the upper edge of the said section and upwardly where the clip is applied to the lower edge of the said section. It will thus be seen that this clip affords a cheap and con-

venient means of connecting the plaster board sections to the studs intermediate the vertically-disposed joints of the said board sections.

Now, referring to the form of construction illustrated in Figs. 7 to 11, inclusive, I will designate the clip by the numeral 15, the body of the clip being U-shaped, as shown at 16, and having its extremities 17 bent in opposite directions. Where this form of construction is employed, the U-shaped member of the clip is caused to straddle the stud 6 at the horizontal meeting edges of two plaster board sections,—see Fig. 13,—while one of its extremities 17 engages the plaster board section above the horizontal joint, and the other extremity 17 engages the section below the same joint, the U-shaped body member of the clip being in line with the joint and disposed between the two board sections. This form of the clip may be advantageously used at the horizontal joints of the plaster board sections, between the floor and the ceiling, or any other two surfaces, where the plaster board sections are not arranged in staggered relation. At the top and bottom of the stud, however, in this form of construction, I prefer to employ the clip 7, the clip at the top having its hook-shaped extremities 12 extending downwardly, while the one at the bottom has its corresponding parts directed upwardly.

Having thus described my invention, what I claim is:

In combination, a vertical stud, sheeting applied thereto upon one side, a U-shaped clip adapted to straddle the stud, said clip being inclined upwardly toward the sheeting side of the stud and having its extremities bent downwardly into a vertical plane to engage the sheeting upon the side remote from the stud.

In testimony whereof I affix my signature in presence of two witnesses.

LOUIS F. JACKSON.
